UNITED STATES PATENT OFFICE.

LOUIS MARTIN, OF MUNCY, PENNSYLVANIA.

SNOWPLOW.

Application filed July 20, 1926. Serial No. 123,676.

The invention relates to snow plows and has for its object to provide a simple device of this character which may be easily and quickly connected beneath a conventional form of bob sled and forwardly of the rear truck thereof, and with which snow plow roads may be quickly cleared particularly in rural districts.

A further object is to provide a snow plow adapted to be attached to opposite sides of a reach of a bobsled forwardly of the rear truck and comprising rearwardly diverging scraper blades terminating beyond the opposite sides of the bob-sled and provided with upwardly, forwardly and outwardly curved deflecting portions, which deflecting portions will easily and quickly turn the snow to opposite sides of the roadway.

20 A further object is to provide the upper inner ends of the deflecting blades with opposed U-shaped portions which receive opposite sides of the reach and may be quickly secured to the reach by a single bolt.

25 A further object is to provide the reach with a detachable brace having transversely diverging arms which incline downwardly and are anchored to the blades and which diverging arms brace the blades against inward movement in relation to each other, and also against upward movement during a snow removing operation.

30 A further object is to provide a bob-sled having a front and rear truck with snow scraper blades which scraper blades diverge outwardly and rearwardly from positions between the truck and substantially centrally of the bob-sled, thereby allowing the driver of the sled to operate the same from the forward end thereof and to utilize his weight for preventing the blades from riding over partially solidified snow.

35 With the above and other objects in view the invention resides in the combination and arrangement of parts as hereinafter set forth, shown in the drawing, described and claimed, it being understood that changes in the precise embodiment of the invention may be made within the scope of what is 40 claimed without departing from the spirit of the invention.

In the drawing:

45 Figure 1 is a side elevation of the bobsled showing the snow plow applied thereto.

50 Figure 2 is a top plan view of the bobsled showing the snow plow.

Figure 3 is a transverse sectional view taken on line 3—3 of Figure 1.

Referring to the drawing, the numeral 1 designates the top of the bob-sled and 2 a reach disposed beneath said top and which reach is connected to a bolster adjacent the rear end of the sled and to the king bolt 4 adjacent the forward end of the sled. The bolster 3 is provided with a fixed sled 5 adjacent the rear end of the sled and pivotally mounted on the king bolt 4 adjacent the forward end of the bob-sled is a steering sled 6 to which draft animals may be attached in any suitable manner.

60 Disposed beneath the reach 2 forwardly of the fixed sled 5 are rearwardly diverging scraper blades 7 which scraper blades are concaved and diverge outwardly forwardly of the fixed truck 5 whereby snow scraped from the roadway will be conveyed and deflected outwardly away from and to opposite sides of the bob-sled thereby clearing a roadway for a sufficient width to allow the 65 passage of vehicles. The outer ends of the blades 7 are provided with upwardly, outwardly and forwardly curved portions 8, which as the snow is accumulated in the ends of the blades curves said snow upwardly, forwardly and outwardly beyond the ends of the blades. The forward ends 9 of the blades 7 are vertically disposed and at their upper ends terminate in opposed 70 U-shaped portions 10 which receive the opposite sides of the reach 2 and through 75 which portions 10 and the reach a bolt 11 extends, therefore it will be seen that the blades may be easily and quickly attached to the reach from opposite sides thereof, and the construction of the bob-sled as a 80 whole does not vary, and the bob-sled can be used for other purposes by simply removing the blades. Secured to the under- 85 side of the reach 2 by means of a bolt 12 is a brace 13, which brace is provided with 90 downwardly and transversely diverging 95 brace arms 14, the lower ends of which are anchored at 15 to the rear sides of the blades 7 and prevent inward movement of 100 said blades as well as upward movement of 105 the blades, and in combination with the bolt 11 rigidly holds the blades in position during a snow scraping operation.

105 From the above it will be seen that a snow blade attachment is provided for a 110 conventional form of bob-sled, which attachment may be easily and quickly applied

- to a bob-sled without varying the construction thereof and the blades 7 may be applied to the sled from opposite sides thereof. It will also be seen that by locating the blades 7 between the steering truck or sled 6 and the fixed sled 5, the weight of the operator will be disposed forwardly of the blades 7 on the body 1, thereby insuring a positive scraping operation at all times.
- 10 Members 10 are preferably provided with spaced apertures for the reception of bolts 11, thereby allowing vertical adjustment, for instance where there is sagging of the reach 2. Body member 1 is provided with 15 an opening 10^a for allowing vertical adjustment of said members 10. To further brace the members 7, upwardly extending braces 14^a are provided, which braces are anchored on the bolts 15 and extend upwardly and are 20 anchored to the body 1. Members 7 are provided with runners 7^a which prevent the same from digging into the ground.

The invention having been set forth what is claimed as new and useful is:—

The combination with a rearwardly extending bar disposed beneath a bob-sled and front and rear sleds carried by said bob-sled, of scraper blades, said scraper blades having their front ends in engagement beneath the rearwardly extending bar, opposed U-shaped members carried by the blades and in which the opposite sides of the bar are disposed, a bolt extending through said U-shaped members and the bar, said blades diverging rearwardly and outwardly, a brace 35 connected to the bar rearwardly of the blades, arms carried by said brace and diverging downwardly and outwardly, the outer ends of said arms being anchored to said blades. 40

In testimony whereof I hereunto affix my signature.

LOUIS MARTIN.
